Primary Examiner — Shawn T Gingrich*Assistant Examiner* — Bryan N. Melvin(74) *Attorney, Agent, or Firm* — Brown & Brown IP Law PLLC(57) **CLAIM**

The ornamental design for an electrical switching element as shown and described.

DESCRIPTION

Figure 2.1 is a perspective view of the electrical switching element in accordance with my new design;

Figure 2.2 is a right side view thereof;

Figure 2.3 is a left side view thereof;

Figure 2.4 is a rear view thereof;

Figure 2.5 is a front view thereof;

Figure 2.6 is a bottom view thereof; and

Figure 2.7 is a top view thereof.

The portions shown in broken lines are for illustrative purposes only and form no part of the claimed design.
